ROTARY PRINTING PRESS

Emory W. Worthington, Chicago, Ill., assignor to
 The Goss Printing Press Company, Chicago,
 Ill., a corporation of Illinois

Application September 27, 1944, Serial No. 555,903

7 Claims. (Cl. 101—248)

1

This invention relates to rotary printing presses and is more particularly concerned with registration devices for such rotary printing presses, and with axial and circumferential adjustments for effecting such registration.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate embodiments of the invention, and together with the description, serve to explain the principles of the invention.

Of the drawings:

Figure 1 is an elevation with certain parts in section of an embodied form of apparatus for effecting registration according to the present invention;

Figure 2 is a cross section of the apparatus of Figure 1, taken on the lines 2—2 of Figure 1; and

Figure 3 is an enlarged detailed view of the coupling of the apparatus of Figure 1.

In rotary printing presses, for example of the type used for rotogravure printing, it is an advantage to be able to adjust the printing cylinder in an axial direction and independently in a circumferential direction, while the cylinder is running, to effect correct printing register and to adjust for any out of registration in either direction at all times.

Accordingly, it is the object of the present invention to provide novel and improved means for independently effecting axial and circumferential registration, in a rotary printing press.

It is a further object of the invention to provide a simple effective and accurate means for adjusting a cylinder of a rotary printing press, axially and circumferentially, for registration purposes, through the medium of the coupling means between the cylinder driving means and the cylinder.

Generally, in carrying out the present invention, the rotary printing cylinder is driven from a suitable drive shaft through appropriate gearing with coupling means between the cylinder shaft and the driving means. This coupling means, in accordance with the present invention, is so arranged that within the structure thereof

2

there are provided means for effecting axial movements of the cylinder to effect axial registration and independently operable means for effecting circumferential movements of the cylinder to effect circumferential registration. To this end, the driving means which may be of conventional form pass their power to a coupling which preferably comprises one member with two sets of gear teeth thereon and two other independent members each formed with teeth to cooperate with one set of teeth of said first member, one of the gear trains thus formed being axially adjustable, and the other thereof being circumferentially adjustable, without disturbing their effective operations.

Preferably, the coupling comprises an external collar having at one end internally therein one set of teeth, such as helical teeth, and at the other end, internally therein another set of teeth, such as spur teeth, and this collar is rotatably driven from suitable driving means by one member having external teeth, such as helical teeth. The other toothed portion of the collar is adapted to drive an externally toothed member, such as a spur gear, which spur gear is drivingly attached to the cylinder to rotate same.

Means are provided to relatively slide the external spur gear with respect to its cooperating teeth to effect axial movements of the cylinder and separate means are provided to rotatively change the relationship of the internal spiral gear and its cooperating gear to effect circumferential registration. Such means may be photoelectric cell devices operating in accordance with indications of errors in registration of the printed material or alternatively may be manually operated, upon observation of such errors in registration, or by both means.

The coupling, in accordance with this invention, is so constructed that the means for effecting both axial and circumferential registration and the means for driving effectively the cylinder are incorporated therein for simplicity of construction and of operation.

It will be understood that the foregoing general description and the following detailed description as well are exemplary and explanatory of the invention but are not restrictive thereof.

Referring now to the drawings which illustrate one embodiment of the present invention, there is provided a rotary printing cylinder 10 mounted for rotational movements in an anti-friction bearing 12 by a shaft 11. Bearing 12 is carried in a part 13 of the side frame of the printing press. At the portion nearest the cylinder the

shaft 11 has an enlarged portion 14 thereby forming a shoulder 15 which limits the movements of the shaft 11 in one direction through the bearing 12 when the shoulder 15 contacts the inner race of the bearing 12. Shaft 11 is adapted to be moved axially through the inner race 16 of the bearing 12 to permit of axial movements of cylinder 10, as hereinafter brought out, for the purpose of obtaining side registration of the printing cylinder with respect to the paper or the like to be printed.

Shaft 11 extends through the bearing 12 and has an extension 17 which is adapted to be coupled to means for rotating the shaft and thereby rotating the printing cylinder 10. When the cylinder 10 is of the type used for rotogravure printing, it is necessary that this cylinder be readily removed from its bearings and to this end the extension 17 of shaft 11 is adapted to be coupled to the driving means by clamp bar 18 of conventional form. This clamp bar 18 is pivotally mounted in one half of a split collar or flange 19 and has a threaded end 20 which is adapted to be fastened by a nut 24 to a flange (not shown) on the other half of the split collar 19, whereby conventionally, the two split halves of the collar 19 can be clamped about shaft extension 17 with a positive grip using nut 24 and can quickly be released from clamping position and the clamp bar 18 allowed to assume the unattached position of Figure 1, when it is desired to remove shaft 11 from its bearings.

In accordance with the present invention, the coupling means for causing rotational movements of the shaft 11 and thus cylinder 10 have incorporated therein means to permit both axial and circumferential relative movements of the cylinder for both side and circumferential register of the printing cylinder. To this end the driving coupling 25 comprises an outer member in the form of a collar 26 which is adapted to be driven by one gear connected with the cylinder driving means and to pass on the rotatory movements caused thereby to another gear, and therefrom to the shaft 11 of cylinder 10, each of said gears being adjustable relative to the coupling 25 for such registration purposes, as hereinafter brought out.

The power to ultimately rotate the cylinder 10 is obtained from a vertical drive shaft 27 driven from a suitable prime mover (not shown), and mounted for rotation in an anti-friction bearing 28. Bearing 28 is carried by a bearing block 29 which is mounted, as by screw bolts 30, on the side frame member 13.

Splined, as at 24, upon the extending end of shaft 27 is a beveled gear 31 the gear 32 being splined, as at 33, onto an elongated tubular drive shaft 34. Shaft 34 is mounted for rotation in an anti-friction bearing 35, this bearing being supported in a block 36 forming an extension of the bearing block 29 and being supported thereby as by a joint 37. Tubular shaft 34 is intermediately supported by a further bearing 38 in a block 39, this block being also carried by the bearing block 29.

The bearing blocks and their extensions are so arranged that the gears 31 and 32 are enclosed thereby for protection this enclosure being formed by block 36 and its extensions 40, block 39 and its extensions 41 and bearing block 29 and its extension 42.

Tubular shaft 34 extends beyond its bearing 38 and carries at its extremity a helical gear 45. Gear 45 is held in fixed relation to shaft 34 by a

set screw 46 and therefore as the driving shaft 27 rotates, gear 45 will be driven thereby through gears 31 and 32. Gear 45 extends internally of the collar 26 of coupling 25 and is adapted to engage with an internal helical gear within one end of member 26, as illustrated in Figures 1 and 3, whereby as gear 45 is rotated it will in turn rotate collar 26 of the coupling 25.

At the other end of the collar 26 there is another internal gear in the form of an elongated spur gear 48 which meshes with and is adapted to drive a narrow toothed externally threaded spur gear 49 within the member 26. Spur gear 49 is formed on an extension of, or is suitably attached to, the flange 18 which is coupled to the shaft 11 by the clamp bar 18, as hereinbefore described. By this means, the main driving shaft 27 will rotate the tubular shaft 34 through beveled gears 31 and 32 which in turn will rotate gear 45 carrying collar 26 of coupling 25 therewith and thus collar 26, through the medium of intermeshing gears 48 and 49, will rotate flange 18, shaft 11, and cylinder 10, when the clamp bar 18 is in operative or clamping position.

In accordance with this invention, it is desired that the cylinder 10 be rotated relative to its driving means both when at rest and when being driven by such driving means, in order to effect circumferential register while at the same time independently effecting axial movements of the cylinder 10 relative to its driving means, both when the driving means is at rest and is in operative driving position to effect side register.

To effect the side register by axial movements of the cylinder 10, there is provided a rod 50 which is carried internally of tubular shaft 34 and is mounted for increments of longitudinal movements therewithin by means of a screw threaded portion 51 at the end near the bearing 38, this screw threaded portion cooperating with a threaded bore 52 within a member 53 carried by the bearing block 38. Fast upon the threaded end 51 of rod 50 is a handwheel 54, this being fixed to the rod by a pin 55. Thus by turning the handwheel 54 in one or the other direction the rod 50 will be moved longitudinally inwardly or outwardly within the tubular shaft 34 and by providing a relatively fine thread for the cooperating threaded portions 51 and 52, small amounts of movements can be obtained.

Shaft 50 is adapted to directly contact spur gear 49 and move the spur gear 49 and the flange 19 bodily as desired, to effect axial adjustment of cylinder 10. To this end, the free extremity of rod 50 is mounted in a bearing 57, within the body of spur gear 49, to permit easy rotation of the rod 50, and is fixedly associated with the spur gear 49 by means of a cover plate 58 held in place by screws 59 passing within threaded portions of the body of spur gear 49 which retains bearing 57 in place. The extremity of rod 50 is retained from independent movements with respect to flange 19 by a washer 60, held in position by a set screw 61 in a bore 62 located in the end of the rod 50.

In order to accommodate for the longitudinal movements of rod 50 which will cause longitudinal movements of spur gear 49, that is axial movements relative to the axis of the printing cylinder, internal gear 48 within the body of the coupling 25 is made longer than the width of the teeth of the spur gear 49, so that whatever adjustment actually is effected by turning handwheel 54 and moving rod 50 inwardly or outward-

5

ly the spur gear 49 will be in full driven contact with its driving gear 48. Thus axial movements in either direction can be imparted to the shaft 11 and thus the cylinder 10, at all times, even when the drive shaft 27 is effectively driving the cylinder 10 and without, in any way, disturbing or effecting the actual driving means, and accordingly, accurate side register of the cylinder can be obtained while the cylinder is being driven.

In order to effect cylindrical register of cylinder 10 there is provided a rod 60 mounted within a bearing 61 carried by bracket 62, which is supported upon the extension 41 of block 39. At one end and preferably closely associated with handwheel 54 there is a handwheel 63 fixed to the rod 60 by a pin 64. At the other end of rod 60 there is a threaded portion 66 upon which is mounted a rider 67, whereby upon rotation of handwheel 63, rider 67 will move in one or the other direction bodily upon the threaded portion 66 by virtue of a threaded bore 68 within the rider 67. Attached to the rider 67 at the upper end by screw threaded bolts 72 are a pair of levers 70 which are shaped to embrace the body of coupling 25, as specifically shown in Figure 2, being substantially U-shaped levers with right angle extending lugs on each of the arms. The upper lugs 73 are attached by bolts 72 to the rider 67 and the lower lugs 74 are pivotally carried by a pin 75 within a bracket 76 which is mounted upon one flange 77 of bearing block 29. Thus, as rider 67 moves upon the rod 60 the levers 70 are simultaneously swung around their pivot pins 75 and are thus moved relatively longitudinal but in an arcuate path with respect to the body of the coupling 25.

Extending inwardly toward coupling 25 from a central position on each of the levers 70 are rollers 80 mounted upon pins 81 one of which is suitably screw threaded as at 82 in each of the levers 70. Cooperating with the rollers 80 is a groove or track 85 on the body of coupling 25, being as illustrated, formed by a pair of circumferential upstanding lugs 86. The width of the groove or track 85 so formed is substantially the diameter of rollers 80 whereby as the member 26 of coupling 25 rotates, rollers 80 will be clear of direct contact with the inside faces of the upstanding lugs 86 when the apparatus is in its normal position such as is shown in Figure 1 with the levers 70 in a substantially vertical position. Upon rotation of handwheel 63 in either direction the levers 70, as they swing around their pivot 75 in the direction selected, will cause rollers 80 to contact one lug 86 of the track 85 and upon continued movement in that direction the whole of the member 26 of coupling 25 will be bodily moved axially under the urge of rider 67, levers 70, and rollers 80. This movement is ineffective to change the spur gear drive 48-49 since the gear 48 will be moved relative to the gear 49 without effecting this in any way and thus, the axial position of cylinder 10 will be unaffected. However, the movement of the member 26 bodily with respect to the gear 45 will cause a different relative circumferential position between helical gears 45 and 47, with the result that the member 26 will be circumferentially moved relative to the gear 45 and will move gears 48 and 49 simultaneously circumferentially carrying the shaft 11 and thus the cylinder 10 with it. By forming the helical gears 45 and 47 with a relatively small angle, such as 30°, there will be attained a minute adjustment under urge of movements of rider 67 and such movements will have no effect upon the driving means for rotat-

6

ing the cylinder, whereby such circumferential movements of the cylinder 10 can be made while the cylinder 10 is being rotated from the drive shaft 27, and without in any way effecting this drive.

In accordance with this invention, it is therefore possible to adjust the cylinder 10 axially in either direction by use of the handwheel 54, rod 50 and spur gear 49, and separately to effect 10 relative circumferential movements for circumferential register by turning handwheel 63 thus moving levers 70 in one direction or the other and cause relative rotational movement between gears 45 and 47, whereby member 26 of the coupling 25 is circumferentially moved relative to tubular shaft 34. It is to be noted that these adjustments are effected through the medium of one single coupling 25 which coupling simultaneously serves as the means for passing the driving force from shaft 27 through to shaft 11, thus providing a simple unitary and compact means for driving such a rotary printing cylinder with control of both axial and circumferential register in a minute degree.

The invention in its broader aspects is not limited to the specific mechanisms shown and described but departures may be made therefrom within the scope of the accompanying claims without departing from the principles of the invention and without sacrificing its chief advantages.

What is claimed is:

1. In a rotary printing press having a printing cylinder, a shaft for effecting axial and circumferential registration of the cylinder including in combination a coupling comprising a collar having straight teeth at one end, and helical teeth at the other end, a helical gear attached to said shaft and drivingly meshing with said helical teeth, a spur gear attached to said cylinder meshing with said straight teeth and being driven thereby, means axially moving said spur gear relative to said straight teeth on said collar, for axially adjusting said cylinder for registration, while it is being driven and means circumferentially moving said collar relative to said helical gear, for circumferentially adjusting said cylinder for registration while it is being driven.

2. In a rotary printing press having a printing cylinder, a shaft for rotating the cylinder, means for effecting axial and circumferential registration of the cylinder including in combination a coupling comprising a collar having straight teeth at one end and helical teeth at the other end, a helical gear attached to said shaft and drivingly meshing with said helical teeth, a spur gear attached to said cylinder meshing with said straight teeth and being driven thereby, manual means axially moving said spur gear relative to said straight teeth on said collar, for axially adjusting said cylinder for registration, while it is being driven and manual means circumferentially moving said collar relative to said helical gear, for circumferentially adjusting said cylinder for registration while it is being driven.

3. In a rotary printing press having a printing cylinder and a shaft for rotating the cylinder, means for registration of the cylinder including in combination a coupling having a collar formed with internal helical teeth at one end and internal straight teeth at the other end, a spur gear attached to the cylinder having its teeth in mesh with the internal straight teeth to be driven thereby, adjustable means for moving the spur gear bodily within the collar to effect axial

registration of the cylinder, an externally toothed helical gear driven by said shaft and having its teeth in mesh with the internal helical teeth of the collar to rotate the collar, and adjustable means for axially moving the collar relative to the helical gear to effect relative circumferential movement between the meshing helical teeth, and thus to circumferentially adjust the registration of said cylinder.

4. In a rotary printing press having a printing cylinder and a shaft for rotating the cylinder, means for effecting axial and circumferential registration having a collar formed with internal helical teeth at one end and internal straight teeth at the other end, a spur gear attached to the cylinder having its teeth in mesh with the internal straight teeth to be driven thereby, adjustable means for moving the spur gear bodily within the collar to effect axial registration of the cylinder, the width of the teeth of the straight internal gear being greater than the width of the teeth of spur gear to accommodate for such relative axial movements, an externally toothed helical gear driven by said shaft and having its teeth in mesh with the internal helical teeth of the collar to rotate the collar, and adjustable means for axially moving the collar relative to the helical gear to effect relative circumferential movement between the meshing helical teeth, and thus to circumferentially adjust the registration of said cylinder.

5. In a rotary printing press having a printing cylinder and a shaft for rotating the cylinder, means for effecting axially and circumferential registration of the cylinder including in combination a coupling having a collar formed with internal helical teeth at one end and internal straight teeth at the other end, a spur gear attached to the cylinder having its teeth in mesh with the internal straight teeth to be driven thereby, adjustable means including a rotatable screw threaded rod and cooperating threaded collar, said rod being attached to the spur gear, for moving the spur gear bodily within the collar to effect axial registration of the cylinder, an externally toothed helical gear driven by said shaft and having its teeth in mesh with the internal helical teeth of the collar to rotate the collar, and adjustable means for axially moving the collar relative to the helical gear to effect relative circumferential movement between the meshing helical teeth, and thus to circumferentially adjust the registration of said cylinder.

6. In a rotary printing press having a printing cylinder and a shaft for rotating the cylinder, means for effecting axially and circumferential registration of the cylinder including in combination a coupling having a collar formed with internal helical teeth at one end and internal

straight teeth at the other end, a spur gear attached to the cylinder having its teeth in mesh with the internal straight teeth to be driven thereby, adjustable means for moving the spur gear bodily within the collar to effect axial registration of the cylinder, an externally toothed helical gear driven by said shaft and having its teeth in mesh with the internal helical teeth of the collar to rotate the collar, and adjustable

5 means for axially moving the collar relative to the helical gear including a screw threaded rotatable rod having a rider mounted thereon, said rider carrying yoke embracing said collar and bodily moving same axially under urge of said 10 rider, to effect relative circumferential movement between the meshing helical teeth, and thus to circumferentially adjust the registration of said cylinder.

7. In a rotary printing press having a printing cylinder, and a shaft for rotating the cylinder, means for effecting axial and circumferential registration of the cylinder including in combination a coupling having an external collar internally formed at one end with wide straight 20 teeth and at the other end with helical teeth, a narrow tooth spur gear directly attached to the cylinder, and meshing with the straight teeth of the collar to be driven thereby, an externally toothed helical driving gear carried by a hollow 25 drive shaft driven by said shaft, and meshing with said internal helical teeth to rotate said collar, an operating rod attached to said spur gear and passing through said hollow shaft, adjustable means to move said rod in small amounts 30 through said hollow shaft in one or the other direction to axially move said spur gear and cylinder, a pivoted yoke embracing and engaging said collar without retarding its rotation, means to move said yoke about its pivot in small amounts 35 through said hollow shaft in one or the other direction to axially move said spur gear and cylinder, a pivoted yoke embracing and engaging said collar without retarding its rotation, means to move said yoke about its pivot in small amounts 40 to bodily move said collar axially, whereby to relatively alter the circumferential position of the helical driving gear and the collar, spur gear and cylinder.
